UNITED STATES PATENT OFFICE.

PETER JOHN KNAUS, OF CHICAGO, ILLINOIS, ASSIGNOR TO WESTERN ELECTRIC COMPANY, INCORPORATED, OF NEW YORK, N. Y., A CORPORATION OF NEW YORK.

GRINDING AND POLISHING APPARATUS.

Application filed March 18, 1925. Serial No. 15,228.

This invention relates to a grinding and polishing apparatus, and more particularly to an improved apparatus for grinding and polishing cylindrically shaped articles.

6 The present invention is applicable to that class of grinding machines commonly known as "centerless grinders", and particularly to that type of centerless grinders wherein the grinding and feeding wheels are peripherally opposed to each other.

10 The primary object of this invention is to provide a centerless grinding machine which is adapted to rapidly and efficiently grind and polish cylindrical articles.

15 Other objects and advantages of the invention will become apparent in the following detailed description and the novel features of the invention will be particularly pointed out in the appended claims.

20 In the preferred form of the invention the contacting surfaces of both the feeding and grinding wheels are profiled or beveled on the forward edges of their peripheries so that as the article to be ground is passed 25 therebetween it may be abraded to a greater depth and in graduated steps, as illustrated in the accompanying drawings. The rear portions of the wheels may be composed of a relatively finer grade of abrading material 30 and their contacting surfaces are substantially parallel to each other, thereby producing a polishing action which is of considerable value. In a modified form of this invention the grinding and feeding wheels are 35 not profiled, but the same general result is obtained by inclining the work support relative to the axis of the grinding wheel.

In the accompanying drawing,

40 Fig. 1 is a front elevation, partly in section, of a centerless grinding machine embodying the features of the present invention, and

Fig. 2 is a fragmentary detail view of the feeding and grinding wheels.

45 Referring now to the drawings in detail wherein like reference characters designate corresponding parts throughout the several views. 10 denotes a main frame of hollow or box like construction, near the upper portion of which is formed a bed or table 11 and a well or cavity 12, which receives water supplied to the work from a nozzle 17 connected to any suitable supply source (not shown). Rotatably journaled in suitable bearings supported by the frame 10 is a hori-

zontal shaft 13 to which is secured a pair of annular disk members 14 and 15. Fas-tened between the disk members 14 and 15 by means of a nut 29 is an annular grind-ing wheel 16 which may be composed of any suitable abrading material.

Cooperating with and peripherally op-posed to the grinding wheel 16 is a feeding and governing wheel 18 which is likewise of annular form and may be composed of any suitable material that is readily dressed. The feeding wheel 18 is clamped between a pair of annular disk members 19 and 20, carried by a spindle or arbor 21. The clamping disks 19 and 20 are firmly pressed 70 into and held in binding engagement with the feeding wheel 18 by a nut 30 threaded upon the spindle 21. The function of the feeding and governing wheel is, as its name would suggest, to govern or control the rotation of the work, to support it properly in contact with the periphery of the grinding wheel, and to effect the axial traverse or feeding of the work by acting upon the well-known principle of a skew-roll.

As shown in Fig. 1, the centers of the grinding and feeding wheels are preferably in the same horizontal plane. When it is desired to effect an automatic axial feed or traverse of the article being ground, the 75 feeding wheel 18 is tipped on its central point at a predetermined angle to the grinding wheel 16 as best shown in Fig. 2, thereby causing an oblique relation of the axis of the feeding wheel relatively to the axis 80 of the work. This causes the work to ad-vance with a spiral or screw-like motion across the face of the grinding wheel, thus presenting the entire surface of the work 85 throughout the length thereof progressively 90 to the grinding face.

In the drawings, the relation between the diameters of the grinding and feeding wheels is shown as approximately three to two, but neither this nor any other specific 100 relation is essential to the successful opera-tion of the machine. Both the feeding and the grinding wheels are rotated in a clock-wise direction when viewed from the front of the machine, the larger or grinding wheel 105 moving downwardly and the smaller or feed-ing wheel moving upwardly where they contact with the work. Suitable gearing is pro-vided whereby the rotation of the governing 110 and feeding wheel is made relatively slow

and that of the grinding wheel is made relatively fast. In practice, the speeds and the ratio of speeds of the wheels 16 and 18 may vary within reasonable limits depending somewhat upon the nature of the article being ground and the amount of material which it is desired to remove in a given time or within a given traverse of the work.

Positioned immediately in front of and 10 midway between the grinding wheel 16 and the feeding wheel 18 is a horizontally disposed work support 25 of well known construction which serves as a rest for the article being ground as it advances through 15 the machine.

Any suitable mechanisms may be provided for adjusting the feeding wheel 18 towards and away from the grinding wheel 16 to accommodate work of different diameters and also for tipping the feeding wheel 18 at any desired angle to cause a traverse of the work at any predetermined speed. The mechanisms for performing these operations, which have been shown more or 25 less schematically in the accompanying drawing, are well known in the art and since they form no part of this invention, it is thought that a further illustration and detailed description thereof is unnecessary.

30 The grinding and feeding wheels 16 and 18 are profiled or beveled on the forward edges of their respective peripheries as indicated at 26 and 27, respectively, (Fig. 2). By this construction the blank may be subjected to a substantially deeper abrasion and 35 at graded depths as the blank advances through the machine. This is an important improvement in the art of centerless grinding, particularly for grinding articles of a

relatively soft material, such as rubber, fibre, carbon, etc., since it decreases the number of times that a given article must be passed through a machine to remove a predetermined amount of material. However, it is obvious that the invention is not limited to 45 grinding articles of such material and is only limited by the scope of the appended claims.

The rear portions of the wheels 16 and 18 may be composed of a relatively finer grade 50 of abrading material and their contacting surfaces are substantially parallel to each other as indicated at 22 and 23, thereby providing a polishing action for the ground article as it emerges from the machine. 55

What is claimed is:

1. In a grinding machine, a grinding wheel and a feeding wheel peripherally opposed to the periphery of said grinding wheel, said grinding and feeding wheels having the forward edges of their peripheries profiled and the rear edges of their peripheries parallel to each other.
2. In a grinding machine, a grinding wheel, a feeding wheel peripherally opposed to the periphery of said grinding wheel, means for rotating said grinding and feeding wheels, and means for supporting and guiding an article to be ground between the peripheries of said wheels, the forward portions of said wheels being profiled to abrade said article at graded depths, and the rear portions of said wheels being parallel to each other to polish said article as it passes therebetween.

In witness whereof, I hereunto subscribed my name this 3rd day of March A. D., 1925.

PETER JOHN KNAUS.
